MERCURY LIGHT

William S. Brian, Owensboro, Ky., assignor to
General Motors Corporation, Detroit, Mich., a
corporation of Delaware

Application December 4, 1941, Serial No. 421,587

9 Claims. (Cl. 176—13)

This invention relates to means for producing ultraviolet light rays and more particularly to mercury tubes operated by low voltage for said ultraviolet production.

There are many instances in which it is desired to produce ultraviolet light rays for various uses and it has been believed necessary to apply high voltages to a confined body of mercury in order to obtain said rays in sufficient quantity to be useful. This usually necessitated the use of large sources of power and transformers and expensive installations. These were in most cases bulky and heavy and not readily portable.

With a view to providing some means for moving troops or materials at night without disclosing such movement to the enemy, or during blackout periods, sufficient identification of objects may be obtained by painting the same, such as posts or poles along a highway, with luminous paint and then causing ultraviolet rays to impinge thereupon. This will enable the objects to be viewed at some horizontal distance and if the source of rays is mounted upon mobile vehicles, they may proceed with substantially no visible light which might be detected by others at any great distance and almost no vertical distance so that occupants of planes would be unable to see them.

It is therefore an object of my invention to provide a readily portable source of ultraviolet light.

It is a further object of my invention to provide a source of ultraviolet light which will operate from a low voltage source.

It is a still further object of my invention to provide a mercury tube source of ultraviolet rays which is inexpensive, efficient, will operate from low voltage and have long life.

With the above and other objects in view, which will become apparent as the specification proceeds, my invention will be best understood by reference to the following specification and claims and the illustrations in the accompanying drawing, in which:

Figure 1 is a vertical section through a mercury tube with its attendant circuit;

Figure 2 is a partial section through the lower portion of the tube illustrating its action; and

Figure 3 is a sectional view taken on line 3—3 of Figure 1.

Referring now more specifically to the drawing, there is shown in Figure 1 an elongated hollow casing 2 formed of insulating material. In the lower end of the casing is secured an in-

5 sulating disc 4 which has a concave upper surface 6 and a central opening 8 therethrough in which is supported one end of an electrode 10. This electrode is made of a material having a higher resistance to current flow than mercury and in this instance is formed of carbon. A metal electrode 12 is secured to the carbon and carried by the end of the casing.

10 Into the side of the casing 2 there is injected a second electrode 14 which projects into the central aperture for a short distance. There is also provided a third metallic electrode 16 which projects down from the upper end of the casing a considerable distance within the central aperture. Secured to this upper electrode is a large cylindrical member 18 formed of electrical insulating material which surrounds and entirely encloses the lower projecting end of the electrode 16 but allows a small portion of the electrode adjacent its support in the casing to be exposed as shown at 20. This portion 20 has within a crater 21 in the top of the cylindrical member 18. Within the casing there is a substantial amount of mercury 22 which entirely covers the two lower electrodes and extends up around the lower end of the cylindrical member 18.

15 A conductive line 24 is connected to electrode 14 and also to one terminal of a battery 26 and to one side of the secondary 28 of a transformer. The electrode 16 is connected by line 30 to the opposite side of the secondary 28 and connected directly across the secondary 28 is a condenser 32. The opposite terminal of the battery 26 is connected to the primary 34 of the transformer, the opposite side of which is connected by line 36 to the electrode 12.

20 The operation of the device is as follows:

25 It will be noted that there is a continuous circuit from one terminal of the battery 26 through line 24, electrode 14, mercury 22, electrode 10, electrode 12, line 36, transformer primary 34, back to the opposite battery terminal. As current flows through this circuit, it will cause heating of the mercury in contact with the upper surface of the carbon electrode 10 in sufficient quantity to cause a vaporization of the mercury at that point. This vaporization will be sufficient to entirely isolate the liquid mercury from the electrode and thus break the conductive circuit which is best shown in detail in Figure 2. As soon, however, as this happens, current ceases to flow in this circuit, and the source of heat thus being removed, the vapor will condense and the circuit will again be re-

formed. This operation will continue as long as current is supplied to the system. I have thus provided an automatic interrupter which will provide a series of pulsating currents.

Since this current also flows through the primary 34 of the transformer, each time current is started and stopped there will be induced in the secondary 28 a higher voltage which is applied to the upper electrode 16 which will then tend to cause an arc between it and the mercury pool. This arc of course is a mercury arc and is carried by the mercury vapor adjacent the upper surface of the pool and this is the source of ultraviolet rays.

I have found, however, that if the electrode 16 is merely allowed to project downwardly toward the mercury pool, the arc formed, which is the source of some ultraviolet rays, is not as satisfactory as might be desired. Therefore, I have applied to the extending end of the electrode 16 a long cylindrical member 18 formed of electrical insulating material and projects down into the mercury bath, causing the same to rise up around the sides of the same and between it and the casing. This causes the arc 25 to occur at various places around the circumference which gives the effect of spreading. Since this area is restricted, the mercury vapor will run at a higher temperature but it tends to keep the arc migrating around the torus instead of concentrating it at one place which assists in keeping the interior of the transparent casing freer from burning than with the straight arc. The metal which may sputter from the exposed section 20 of the upper electrode is deposited on the surface of the crater 24 and thus prevented from discoloring the inside of the transparent casing 2 to cut down the light transmitted therethrough. I have therefore produced a more efficient, simpler, and long lived source of ultraviolet rays.

I claim:

1. In a light source, a casing, a pair of electrodes supported in spaced relation by the casing, one of said electrodes being in a liquid state and means formed of insulating material mounted upon and encasing a portion of the other electrode and projecting down into the liquid electrode for a substantial distance, thus forcing the liquid up around it.

2. In a light source, a casing formed of transparent electrical insulating material, an electrode supported in one end of the casing, a pool of mercury within the casing, means to apply a potential difference to the mercury and the electrode of such proportions as to cause an arc to be set up and insulating means mounted upon the projecting end of the upper electrode and encasing a portion thereof and extending down into the mercury a substantial distance causing the mercury to rise up around it whereby the arc will be spread out and cause to migrate around the insulating means.

3. In a light source, a casing formed of transparent electrical insulating material, an electrode supported in one end thereof, a pool of mercury within the casing, means to apply a potential difference to the mercury and the electrode of such proportions as to cause an arc to be created, a protective member of insulating material supported on and encasing a portion of said upper electrode and extending down into the mercury for a substantial distance, said member being roughly circular in cross section thereby causing the mercury to rise in a ring

around it and cause the arc to be generated between this ring and the upper exposed portion of the electrode, whereby the arc will be spread out and caused to migrate.

5. In a light source, a casing formed of transparent electrical insulating material, an electrode supported in one end thereof, a pool of mercury within the casing and spaced from the electrode, means for applying a potential difference to the mercury and the electrode of sufficient proportions to cause an arc to be formed, an insulating member of the same general configuration as the casing but of smaller cross section so that it will fit within the casing and extend down into the mercury, forcing the latter up around the sides, carried by and encasing the lower end of the upper electrode whereby the arc is developed between the area of mercury between the casing and the central member and the upper electrode to provide an arc which is spread out.

5. In a light source, a cylindrical casing of transparent electrical insulating material, a plurality of electrodes carried by and projecting to points within the casing, at least one of which is formed of a material of substantial resistance, a pool of mercury within the casing and extending between two of the electrodes and a member of insulating material carried by another electrode and partially encasing the same and extending down into the mercury, thereby providing a substantially cylindrical path for an arc from the upper mercury surface to the exposed part of the last named electrode and means to apply a potential difference to the electrodes to cause such arc to be drawn.

6. In a light source, a cylindrical casing formed of transparent insulating material, a plurality of electrodes carried in spaced relation by the casing, a pool of mercury within the casing and interconnecting at least two of the electrodes, a cylindrical insulating member of smaller diameter than the inner diameter of the casing carried by a third electrode, encasing a portion thereof and extending into the mercury pool to force the mercury up into the space between this member and the casing, and means for applying a potential difference to all of the electrodes whereby an arc will be generated between the mercury surface and the exposed portion of the last mentioned electrode.

7. In a light source, a cylindrical casing formed of transparent insulating material, a plurality of electrodes carried in spaced relation by the casing, one of said electrodes having a higher resistance to the flow of electrical current than mercury, a pool of mercury within the casing and interconnecting the electrode of higher resistance and one of the other electrodes, circuit means for applying a low voltage to these two electrodes whereby autonomic interrupter action will be established, a transformer coil in this circuit, a second circuit connected to a third electrode and the source, a transformer secondary coil cooperating with the first coil connected in the second circuit whereby higher voltage is induced in the second circuit and applied to the third electrode to draw an arc between it and the mercury pool and insulating means encasing a portion of the third electrode and extending down into the mercury pool to expand the arc.

8. In a light source, a casing formed of transparent electrical insulating material, an electrode supported in one end of the casing, a pool of mercury within the casing, means to apply a potential difference to the mercury and the electrode

of such proportions as to cause an arc to be set up between the two, a cup-shaped insulating member mounted on the electrode end to shield the same and extend upon between the electrode and the sides of the casing to cause the arc to be formed up over the top of the member and prevent any metal particles from the electrode from splashing on the inner surface of the casing to darken the same but to catch them on the inner cup surface.

9. In a light source, a casing formed of transparent electrical insulating material, an electrode supported in one end of the casing, a pool of mercury within the casing, means to apply a po-

tential difference to the mercury and the electrode of such proportions as to cause an arc to be set up between the two, a cup-shaped insulating member mounted on the projecting electrode end and extending down into the mercury to force the same up around the sides thereof and extend up between the electrode and the sides of the casing to cause the arc to be formed over the top of the member to the upper mercury surface and prevent any splatter to the inner casing surface from the electrode to cause discoloration of the same.
